UNITED STATES PATENT OFFICE.

HOUISON THOMPSON, OF ST. PAUL, MINNESOTA.

DESIGN FOR AN ERASER.

SPECIFICATION forming part of Design No. 29,486, dated October 18, 1898.

Application filed September 16, 1898. Serial No. 691,111. Term of patent 3 $\frac{1}{2}$ years.

To all whom it may concern:

Be it known that I, HOUISON THOMPSON, a citizen of the United States, residing at St. Paul, in the county of Ramsey and State of Minnesota, have produced and invented a certain new and original Design for an Eraser, of which the following is a specification.

This invention relates to erasers for removing ink marks from paper, and the design thereof is illustrated in the accompanying drawing, in which the figure represents a perspective view of the eraser.

The leading feature of my design is the definite shape of the eraser, as herein shown and described.

Referring to the drawing, A represents the

body of the eraser, which is oblong, the ends B C and one edge D being flat and the sides slightly concaved, while the remaining edge G is convex and with an abrasive surface. 20

Having thus described my invention, what I claim as new is—

The design for an eraser substantially as herein shown and described.

In testimony whereof I have hereunto set 25 my hand in the presence of two subscribing witnesses.

HOUISON THOMPSON.

In presence of—

C. N. WOODWARD,
ERIC NORTON.
